UNITED STATES PATENT OFFICE.

THOMAS GRISWOLD, JR., AND EDWIN O. BARSTOW, OF MIDLAND, MICHIGAN,
ASSIGNORS, BY MESNE ASSIGNMENTS, TO THE CLEVELAND TRUST COMPANY,
TRUSTEE, OF CLEVELAND, OHIO, A CORPORATION OF OHIO.

OXYGEN-GENERATOR.

1,140,373.

Specification of Letters Patent.

Patented May 25, 1915.

Application filed August 18, 1910. Serial No. 577,818.

To all whom it may concern:

Be it known that we, THOMAS GRISWOLD, Jr., and EDWIN O. BARSTOW, citizens of the United States, and residents of Midland, county of Midland, and State of Michigan, have jointly invented a new and useful Improvement in Oxygen-Generators, of which the following is a specification, the principle of the invention being herein explained and the best mode in which we have contemplated applying that principle, so as to distinguish it from other inventions.

The present invention relates to gas generators, and has particular regard for the provision of a machine for the generation of oxygen. The generator is especially adapted to perform the process wherein oxygen gas is generated from chlorid of lime or "bleaching powder," which is mixed with water and to which is added a catalyzer. This process may be performed by mixing with a suitable amount of "bleaching powder" a small percentage of copper sulfate or other analogous catalyzer, and to the mixture of the two water is added, and the temperature of the whole mixture is then raised. The consequent reaction results in the liberation of oxygen while calcium chlorid is formed which remains in solution. Various uses of oxygen in the industrial arts, as for instance, oxy-acetylene welding, demand that oxygen shall be generated in some convenient and cheap manner from an inexpensive material, and it is the object of the present invention to provide an apparatus adapted to this economical generation of oxygen. To the accomplishment of these and related ends, said invention, then, consists of the means hereinafter fully described and particularly pointed out in the claims.

The annexed drawings and the following description set forth in detail certain mechanism embodying the invention, such disclosed means constituting, however, but one of the various mechanical forms in which the principle of the invention may be used.

In said annexed drawings:—Figure 1 is a front elevation of an apparatus embodying our invention; Fig. 2 is a side elevation thereof; Fig. 3 is a central vertical section

with parts of the complete apparatus removed; Fig. 4 is a plan of the apparatus with certain parts removed; Fig. 5 is a central section of a washing chamber; Figs. 6 and 7 are respectively top and bottom plan views of such washing chamber; Fig. 8 is a central vertical section of a second washing chamber; Figs. 9 and 10 are respectively top and bottom plan views of such second washing chamber; Fig. 11 is a detail of one pipe; and Figs. 12 and 13 are plans of two co-operating elements forming a grinder.

The apparatus comprises a cylindrical receptacle A which may be made of any suitable material and lined, if preferred, with some material adapted to resist the chemical actions, the receptacle being provided with any suitable support. The top of the receptacle A is open, and between its top and bottom it is provided with a horizontally arranged hopper shaped partition a, so that it divides the receptacle A into a lower chamber B which forms a generating chamber, and an upper chamber C which forms a mixing chamber. A pipe b is supported from the partition a, opening into the bottom of the mixing chamber C and extending to a level near the bottom of the chamber B. The partition a adjacent the upper end of the pipe b is provided with inwardly extending corrugations or ribs a'. Extending through the two chambers C and B, and arranged to be driven above the receptacle A by suitable gearing, is a rotatable shaft D which extends downwardly through the pipe b. The shaft D is provided with outwardly extending corrugations or ribs d adjacent to the projections a' with which the partition a is provided. The shaft D is furthermore provided with a plurality of radial arms d' borne near the bottom of the mixing chamber C, and also with a plurality of radial arms d'2 borne by said shaft near the bottom of the generating chamber B. The receptacle A is provided with a suitable man-hole a² and with a steam supply pipe a³, while at another point in its cylindrical wall it is provided with a discharge pipe a⁴ which is upwardly inclined as clearly shown in Fig. 2, the man-hole and pipes a² and a⁴ entering the generating chamber B.

Supported from the top of the receptacle

A by a suitable bracket is a cylindrical tank E which forms a washing chamber and into which leads from the generating chamber a pipe e. The pipe e leads from 5 the generating chamber B near the top thereof and into the top of the washing chamber E and depends therethrough to a point near its bottom, the pipe e being perforated at its lower end in the chamber E 10 as disclosed at e' in Fig. 5. A pipe g which is connected with a suitable water supply extends downwardly through the top of the chamber E to a point near its bottom, while a stand-pipe e² leads downwardly through 15 the bottom of the chamber E and exteriorly thereof is recurved and then opens into the mixing chamber C, the pipe e² having a diaphragm e⁴ supported slightly above the opening in its top within the chamber E. 20 The chamber E is provided with an outlet pipe e² through its top. It sometimes is advisable to subject the gas drawn off from the washing chamber E to a second washing before it is finally led to a storage or consuming plant, and in the drawing we have 25 shown the draw-off pipe e² extending from the washing chamber E through the top of a second washing chamber F and downwardly therein to a point near its bottom. 30 The chamber F is provided with an outlet pipe f which leads finally to the gas storing or consuming plant, but the gas may also escape through the pipe f' into the generating chamber B. Although a second 35 washing of the gas is sometimes advisable, it is not always necessary, and in the latter case, the gas will be conducted directly from the chamber E to the storage or consuming plant. In either case the pipe f' will be 40 in direct communication with the gasometer. We have shown the tank G arranged on a suitable frame work supported by the receptacle A as constituting a convenient form of water supply for the generator. This 45 tank G has a pipe g extending downwardly into the washing chamber E as has been described. The inlet into the tank G is controlled by a float operated valve g², while the outlet through the pipe g is controlled 50 by a floating discharge valve which is operated by a chain device g', by which the valve may be pulled from its seat, this water tank thus being the familiar flush tank.

In the operation of the device a suitable 55 amount of bleaching powder is put into the mixing chamber. This may be conveniently done by raking or shoveling it out of the usual packages in which it is bought and sold, one form of which is shown at c 60 in Fig. 3. The stirring mechanism is then started and the flush valve of the tank G opened by pulling upon the chain, whereupon the water content of G is run into the mixing chamber by way of the washer E

and the pipe e⁸. The water and bleaching powder are mixed together and the powder is washed down the pipe b into the generating chamber. Previously, however, to such mixture being washed down, it has been thoroughly stirred by the arms d' in the 65 mixing chamber carried by the vertical shaft, so that any lumps of material would be broken up, and it is further ground to a suitable fineness by the coöperating projections d and a' on the shaft and the partition, which thus form a grinder. The catalyst may be added to the bleaching powder and water if desired, but we have found it convenient to mix up the small amount of catalyst required with water in a pail 70 and to throw it into the mixing chamber just after the bleaching powder has been washed down. We then add a second pail of water to insure that the catalyst has been washed out of the pipe b into the mixing chamber. This feature of practice will vary with the nature of the catalyst used and the temperature at which the liberation of oxygen begins. The mixture of powder, catalyst and water passes down 75 through the pipe into the generating chamber where the reactions occur, and these reactions are considerably hurried by the stirring arms carried in such chamber by the rotating shaft. The temperature of the 80 mass within the generating chamber is raised by leading directly into such chamber steam through the steam inlet pipe, or, if preferred, by any other application of heat. The reactions result in the liberation of oxygen 85 gas which rises within the generating chamber and flows off through the pipe e which leads into the washing chamber. It there passes upwardly through the water 90 which is standing in said chamber and is thus washed of any foam and spray which 95 accompanies the gas as it is liberated from the generating chamber. The gas after being thus washed may, as has been indicated, be led directly to where it is to be used. Under some circumstances, however, 100 the generated oxygen may be accompanied by a small amount of chlorin, and if so, it is desirable that this chlorin be washed out. This may be conveniently done by leading 105 the gas through the second washing chamber which is charged with an alkaline solution such as caustic soda. It may be noted that the alkaline solution will neutralize but very slowly, and hence need not be replenished except at infrequent intervals. The spent charge in the generating chamber is then drawn off through the draw-off pipe, and as this is done oxygen reënters the generating chamber through the pipe f' which 110 leads from the delivery pipe f and the gas storage (not shown) and fills the generator 115 in volume equal to that of the spent charge 120 125

of liquor which is drawn off. Oxygen only is therefore found above the liquor level within the chamber, and reentrance of air into the generator is effectively provided against.

The apparatus as a whole, therefore, provides a cheap, simple and extremely efficient means for generating oxygen, and it, of course, may be equally adapted to the generation of other gases where such generation involves the mixing of a granular or powdered solid with a liquid and with or without a catalyzer, and the subsequent elevation of the temperature of the mixture. It will be noted that the stirring arms which are adapted to stir the mixture in both the generating and the mixing chambers are carried and actuated by the same shaft which passes down through the pipe connecting the two chambers, and therefore, a distinct advantage is secured in the obviation of any necessity for a stuffing box for the shaft where it passes into the generating chamber. The grinder is also conveniently connected with the same shaft, and so the grinding and constant stirring of the material is effected by the simple rotation of a single shaft. This thorough mixing and grinding of the material both before and while it is in the generating chamber, greatly increases the rapidity of the reactions, and hence the capacity of the machine. Furthermore, the washing chamber, through which the gas is washed, is so connected with the mixing chamber that any foam and spray escaping thereinto with the gas and retained in such washing chamber will be again washed back by the water supply into the mixing chamber when the next charge of water is introduced.

The diaphragm supported above the stand-pipe in the washing chamber prevents the whirl of water thereinto from drawing with it oxygen contained in the washing chamber.

It may be additionally noted that the various washing chambers and the generating chamber are provided exteriorly with glass gages a^5 so that the attendant may easily ascertain at all times the amount of liquid contained within the respective chambers. The generating chamber is provided with a thermometer a^6 whereby the temperature of the mass within such chamber may be easily noted, and the chamber is also provided with a man-hole which will, at desired intervals, permit a thorough cleaning of the apparatus.

Although the water tank G with its inlet and outlet valves as shown is not essential to the operation of the device and any source of water may be used which will furnish it in sufficient quantities, yet we find the arrangement shown to have the advantage of maintaining automatically a roughly measured quantity of water instantly available

for the charge. Other means of controlling the water supply to this storage tank G and for drawing its contents may be substituted.

Other modes of applying the principle of our invention may be used instead of the one explained, change being made as regards the mechanism herein disclosed, provided the means stated by any of the following claims or the equivalent of such stated means be employed.

We therefore particularly point out and distinctly claim as our invention:—

1. A gas generator, comprising a generating chamber, a mixing chamber separate therefrom but connected therewith, a mixing device in said mixing chamber, a washing chamber, connections from the washing chamber to the mixing chamber and connections from the generating chamber to the washing chamber.

2. A gas generator, comprising a generating chamber, a mixing chamber separate therefrom but connected therewith, a mixing device in said mixing chamber, a washing chamber, connections from the washing chamber to the mixing chamber, said connections being sealed against the escape of gas therethrough, and connections from the generating chamber to the washing chamber.

3. A gas generator, comprising a generating chamber, a mixing chamber separate therefrom but connected therewith, a washing chamber connected with said generating and mixing chambers, and means for heating said generating chamber.

4. A gas generator, comprising a generating chamber, a mixing chamber separate therefrom but connected therewith, a washing chamber connected with said generating and mixing chambers, and a steam pipe connected to said generating chamber and to a suitable source of supply.

5. A gas generator, comprising a generating chamber, a mixing chamber connected therewith, a washing chamber, a stand-pipe in said washing chamber and opening into the mixing chamber, said pipe being sealed against the escape of gas therethrough, and a pipe extending from the generating chamber into the washing chamber and opening into the latter chamber near the bottom thereof.

6. A gas generator, comprising a generating chamber, a mixing chamber connected therewith, a washing chamber, connections from the washing chamber to the mixing chamber, connections from the generating chamber to the washing chamber, and a fluid supply tank adapted to discharge a quantity of fluid into said washing chamber.

7. A gas generator, comprising a generating chamber, a mixing chamber connected therewith, a washing chamber, connections from the washing chamber to the mixing

chamber, connections from the generating chamber to the washing chamber, a fluid supply tank adapted to discharge a quantity of fluid into said washing chamber, and a second washing chamber connected with said first-named washing chamber.

8. A gas generator, comprising a generating chamber, a mixing chamber connected therewith, a washing chamber, connections from the washing chamber to the mixing chamber, connections from the generating chamber to the washing chamber, a fluid supply tank adapted to discharge a quantity of fluid into said washing chamber, and a second washing chamber connected with said first-named washing chamber and with said generating chamber.

9. A gas generator, comprising a generating chamber, a mixing chamber connected therewith, grinding means disposed in the connections between said chambers, and a washing chamber connected with said generating and mixing chambers.

10. A gas generator, comprising a generating chamber, a mixing chamber connected therewith, a washing chamber, grinding means disposed in the connections between said generating and mixing chambers, connections from the washing chamber to the mixing chamber, and connections from the generating chamber to the washing chamber.

11. A gas generator, comprising a generating chamber, a mixing chamber, a pipe opening from the mixing chamber into the generating chamber, said mixing chamber being provided with projections adjacent the opening of said pipe in such chamber, and a rotatable shaft extending through said pipe, said shaft being provided with projections adapted to coöperate with said first-named projections to form a grinder.

12. A gas generator, comprising a generating chamber, a mixing chamber, means for stirring the contents of the generating chamber, means for stirring the contents of the mixing chamber, and means adapted to simultaneously actuate both of said stirring means.

13. A gas generator, comprising a generating chamber, a mixing chamber, a rotatable shaft extending through both of said chambers, arms secured to said shaft within the mixing chamber, and arms secured to said shaft within the generating chamber.

14. A gas generator, comprising a generating chamber, a mixing chamber, a pipe connecting said chambers, a rotatable shaft extending through said pipe, arms secured to said shaft within the mixing chamber, and arms secured to said shaft within the generating chamber.

15. A gas generator, comprising a generating chamber, a mixing chamber, a pipe connecting said chambers, a rotatable shaft

extending through said pipe, arms secured to said shaft within the mixing chamber, and arms secured to said shaft within the generating chamber, said mixing chamber being provided with projections intermediate the opening of said pipe in such chamber and said arms, and said shaft being provided with projections adapted to coöperate with said first-named projections to form a grinder.

16. A gas generator, comprising a generating chamber, a mixing chamber, a pipe connecting said chambers, a rotatable shaft extending through said pipe, arms secured to said shaft within the mixing chamber, arms secured to said shaft within the generating chamber, a washing chamber, connections from said washing chamber to the mixing chamber, and connections from the generating chamber to the washing chamber.

17. A gas generator, comprising a generating chamber, a mixing chamber, a pipe connecting said chambers, a rotatable shaft extending through said pipe, arms secured to said shaft within the mixing chamber, arms secured to said shaft within the generating chamber, a washing chamber, connections from said washing chamber to the mixing chamber, connections from the generating chamber to the washing chamber, and a fluid supply tank adapted to discharge a quantity of fluid into said washing chamber.

18. A gas generator, comprising generating means, mixing means, gas washing means, and means for discharging fluid through said washing means into said mixing means.

19. A gas generator, comprising a generating chamber, a mixing chamber, a washing chamber, and means for discharging fluid through the washing chamber into the mixing chamber.

20. A gas generator, comprising a generating chamber, a mixing chamber, a washing chamber, connections from the mixing chamber to the generating chamber, connections from the generating chamber to the washing chamber, and means for discharging fluid through said washing chamber into said mixing chamber.

21. A gas generator, comprising a generating chamber, a mixing chamber, a washing chamber, connections from the mixing chamber to the generating chamber, connections from the generating chamber to the washing chamber, a stand-pipe in said washing chamber and opening into the mixing chamber, and means for discharging fluid into said washing chamber.

22. A gas generator, comprising a generating chamber, a mixing chamber, a washing chamber, connections from the mixing chamber to the generating chamber, connections

from the generating chamber to the washing chamber, a stand-pipe in said washing chamber and opening into the mixing chamber, means for discharging fluid into said washing chamber, and a second washing chamber connected with said first-named washing chamber.

Signed by us this 15th day of August, 1910.

THOS. GRISWOLD, JR.
EDWIN O. BARSTOW.

Attested by—

ROY WALLIS,
G. LEE CAMP.

It is hereby certified that Letters Patent No. 1,140,373, granted May 25, 1915, upon the application of Thomas Griswold, Jr., and Edwin O. Barstow, of Midland, Michigan, for an improvement in "Oxygen-Generators," were erroneously issued to The Cleveland Trust Company, of Cleveland, Ohio, a corporation of Ohio, as trustee, whereas said Letters Patent should have been issued to *The Dow Chemical Company, of Midland, Michigan, a corporation of Michigan*, as owner of the entire interest in said invention, as shown by the records of assignments in this office; and that the said Letters Patent should be read with this correction therein that the same may conform to the record of the case in the Patent Office.

Signed and sealed this 27th day of July, A. D., 1915.

[SEAL.]

R. F. WHITEHEAD,

Acting Commissioner of Patents.
